CHARLES BENJAMIN MAXSON, OF WESTERLY, RHODE ISLAND, ASSIGNOR OF ONE-HALF
TO JULIAN W. MAXSON, OF WESTERLY, RHODE ISLAND

MACHINE FOR CUTTING SHEET MATERIAL

Application filed August 28, 1928. Serial No. 302,585.

The present invention relates to machines for cutting sheet material.

A machine of a type in common use today for cutting web material, like paper, into sheets, comprises a stationary knife with which cooperates a movable knife mounted upon a rotary drum. The web is fed from above, at a downward incline, into the space between the stationary knife and the drum 10 and toward the under side of the drum, and is cut once corresponding to every revolution of the drum. In order to produce long sheets, it is necessary to feed the web at high speed. It is obvious, however, that the speed of the web must not be materially greater than the peripheral speed of the rotating knife. As a matter of fact, in actual practice, it has never heretofore been possible, so far as known, particularly at high speeds, to have the web even approach this speed of operation of the knife. The knife, after it has cut the web, has a tendency to buckle the cut end of the web, with the result that the successively-cut sheets can not be delivered in smooth, flat condition, but become jumbled up into a hopeless mass.

This tendency exists because the rotary knife and the web approach each other toward the stationary knife from opposite directions.

It is, accordingly, an object of the present invention to improve upon present-day methods of and machines for cutting webs. To this end, the invention resides in the improved machine a preferred embodiment 35 of which is hereinafter described, illustrated in the accompanying drawings, and defined in the appended claims.

In the accompanying drawings, Fig. 1 is a diagrammatic elevation of a paper-cutting 40 machine embodying a preferred embodiment of the present invention; Figs. 2, 3 and 4 are diagrams illustrative of the prior art; and Figs. 5, 6 and 7 are corresponding diagrams illustrating the present invention.

A web of paper 2 is adapted to be fed by any suitable feed mechanism, such as the feed rolls 4 and 6, to a stationary knife 8 with which cooperates a movable knife 10 mounted upon a drum 12 that is disposed to

one side of the stationary knife 8 and rotates about an axis 14. The rotary knife 10 thus moves toward the stationary knife in a forward direction. Corresponding to each revolution of the drum 12, a sheet of paper, that is fed between the knives from a point to the other side of the stationary knife 8 in a direction toward the underside of the drum 12, will be cut by the knives. If the cutter 10 is operated at very high speed, and if the web is fed at a comparably high speed, there is a tendency for the cut end 18 of the web to lag behind the knife 10, as shown in Fig. 3, and thus become deflected upward. This is because the speed of the end 18 of the sheet in the direction of travel of the sheet is greater than the right-line component of the speed of the knife 10 in the same direction, even though their absolute speeds be the same. The result is that the knife 10, blocking the travel of the end 18 of the sheet, causes the said end 18 to catch on the knife 10, and accumulate in loop form in back of the knife 10. Though the operation has thus been described in connection with high speeds, the principle applies also to low speeds.

As the knife 10 rotates further to the position shown, for example, in Fig. 4, the deflection 20 in the cut end 18 of the web becomes more pronounced, with the result that 80 ultimately, after another sheet has been cut, its front end 18 becomes so buckled up as to prevent proper delivery of the sheet.

According to the preferred embodiment of the invention that is herein illustrated and described, however, a projection 22 is mounted in spaced relation and in close proximity to the knife 10 at a point directly rearward of the knife 10 in the direction of rotation 90 of the knife. At certain speeds and under certain conditions, as before stated, the end 18 of the advancing web has a tendency to engage the knife 12 and curl or bulge up on top of it, as illustrated in Fig. 3. The projection 22, however, brushes or directs or deflects the advancing end 18 of the web downward, past the stationary knife 8, thus preventing the end 18 of the web from buckling up. The projection 22, in the form illus- 100

trated, consists of a long bar, approximately equal in length to the length of the knife 10, and screwed in place by a plurality of screws 24 that extend at intervals along the knife 10.

The operation is at first somewhat as illustrated in Fig. 6. As the cutter 10 rotates further, to the position of Fig. 7, corresponding to the position of Fig. 4, the end 18 of the web assumes a position somewhat as shown in the said Fig. 7, permitting the proper delivery of the sheet.

Modifications will readily suggest themselves to persons skilled in the art, and all such are considered to fall within the present invention, as defined in the appended claims.

15 What is claimed is:

1. A machine for feeding and cutting a web having, in combination, a stationary knife, a rotary drum having a cooperating knife projecting therefrom, means for rotating the drum, means for advancing the web between the knives in a direction toward the underside of the drum to cause the web to become cut by the knives, the speed of advance of the web being such relatively to the speed of rotation of the rotary knife that, after the knives have cut the web, the advancing, cut end of the web has a tendency to engage the rotary knife and curl or bulge on top of it, and a member projecting from the drum in spaced relation and in close proximity to the rotary knife at a point directly rearward of the rotary knife in the direction of rotation of the rotary knife for directing the advancing, cut end of the web downwardly past the stationary knife toward the underside of the drum.

2. In a machine for feeding and cutting webs, a stationary knife, a movable knife, means for feeding a web in a diagonal direction between the knives at a speed, relatively to the movable knife, such that, after the knives have cut the web, the advancing cut end of the web has a tendency to engage the movable knife and curl or bulge up on top of it, and means for directing the advancing cut end of the web downwardly past the stationary knife.

3. In a machine for feeding and cutting webs, wherein the web is advanced from a point to one side of a stationary knife into the path of travel of a cooperating movable knife that is moved toward the stationary knife in a forward direction from a point to the other side of the stationary knife, the speed of advance being such, relatively to the speed of the movable knife that, after the knives have cut the web, the advancing cut end of the web has a tendency to engage the movable knife and curl or bulge up on top of it, means disposed in spaced relation and in close proximity to the movable knife at a point directly rearward of the movable knife in the direction of movement of the knife for directing the advancing cut edge

of the web downwardly past the stationary knife.

In testimony whereof, I have hereunto subscribed my name.

CHARLES BENJAMIN MAXSON.
